UNITED STATES PATENT OFFICE.

JOHN KIEWICZ, OF BOSTON, MASSACHUSETTS, ASSIGNOR TO THE REECE BUTTONHOLE MACHINE COMPANY, OF BOSTON, MASSACHUSETTS, A CORPORATION OF MAINE.

THREAD-TRIMMING DEVICE FOR SEWING MACHINES.

Application filed February 26, 1921. Serial No. 447,988.

To all whom it may concern:

Be it known that I, JOHN KIEWICZ, a citizen of the United States, resident of Boston, county of Suffolk, State of Massachusetts, ⁵ have invented an Improvement in Thread-Trimming Devices for Sewing Machines, of which the following description, in connection with the accompanying drawing, is a specification, like characters on the drawing ¹⁰ representing like parts.

This invention relates to thread trimming devices for sewing machines of that type which are constructed to sew a short seam and then automatically come to rest (such ¹⁵ for instance as buttonhole sewing machines), and said invention relates particularly to that class of thread trimming devices which is constructed to cut the needle thread close to the work at the end of each sewing operation ²⁰ and hold the cut end until after the first few stitches of the next succeeding sewing operation have been taken and then to cut the end of the thread thus held. This type of thread cutting device will therefore ²⁵ cut the thread twice during each sewing operation, once after the first few stitches have been formed at the beginning of the sewing operation and again after the sewing operation has been completed.

³⁰ Buttonhole sewing machines are usually provided with stitch-forming mechanism and with work-holding means arranged to have a relative movement during the stitching on a buttonhole and some buttonhole ³⁵ sewing machines are constructed so that the stitch-forming mechanism and work-holding means have an additional relative movement just before the stitching operation begins and just after said stitching operation ends, ⁴⁰ such additional relative movement being for the purpose of carrying the parts from buttonhole-cutting position to stitching position and vice versa. These buttonhole sewing machines are usually arranged so that when ⁴⁵ the machine comes to rest at the end of the stitching operation the stitching mechanism and work-holding means are relatively in buttonhole-cutting position.

In some machines the cutting of the buttonhole is accomplished before the stitching ⁵⁰ is done on the buttonhole, while in other

machines the buttonhole is cut after the stitching is completed. In either case, however, when the sewing machine is started the work is first clamped in the work-holding ⁵⁵ means, the work then being in buttonhole-cutting position, and if the machine is of the type wherein the buttonhole is cut before the stitching operation, then the buttonhole cutter operates to cut the buttonhole, after ⁶⁰ which the stitch-forming mechanism and work-holding means have a relative movement to bring the parts into stitching position, or in other words, to bring the work and needle into such relative positions that the stitching may be properly ⁶⁵ done on the buttonhole. At this time the stitch-forming mechanism is set in operation to form the stitches around the buttonhole and during this operation the work-holding means and stitch-forming mechanism ⁷⁰ have a relative feeding movement. When the stitching on the buttonhole is completed the stitch-forming mechanism comes to rest and then the work-holding means and ⁷⁵ stitch-forming mechanism have a further relative movement to bring them relatively into buttonhole-cutting position, in which position the machine comes entirely to rest. If the sewing machine is of the type in which ⁸⁰ the buttonhole is cut after the stitching operation, then the buttonhole cutter will be operated to cut the buttonhole after the parts are relatively in buttonhole-cutting position but before the machine comes entirely to ⁸⁵ rest.

It is one of the objects of my present invention to provide a thread-trimming mechanism of the type above referred to, that is, one which cuts the needle thread twice, once ⁹⁰ at the beginning and again at the end of each buttonhole, and which is actuated to perform its two thread cutting operations by the relative movement between the stitch-forming mechanism and work-holding ⁹⁵ means.

With my invention the cutting of the thread at the end of the buttonhole is accomplished through the relative movement of the work-holding means and stitch-forming mechanism by which the parts are carried from stitching position to buttonhole- ¹⁰⁰

cutting position, and the cutting at the beginning of the buttonhole is accomplished by the relative feeding movement between these parts.

5 In some buttonhole sewing machines the relative movement between the stitch-forming mechanism and work-holding means is secured by moving the stitch-forming mechanism and in other sewing machines it is 10 secured by moving the work-holding means. I have herein chosen to illustrate my invention as it would be embodied in a sewing machine in which the stitch-forming mechanism moves to secure the above-described 15 relative movement but I do not wish to be limited to a sewing machine having this particular feature.

20 In order to give an understanding of my invention I have illustrated in the drawings a selected embodiment thereof which will now be described after which the novel features will be pointed out in the appended claims.

25 Fig. 1 is a side view of a portion of a buttonhole sewing machine having my improvements applied thereto.

30 Figs. 2, 3 and 4 show plan views of the thread-trimming device, said figures showing the position of the parts at different 35 stages in the formation of the buttonhole.

Figs. 5 and 6 are views illustrating the 40 operation of the switch cam which controls the movement of the thread gripping member.

45 Fig. 7 is a sectional detail view showing the finger 32.

Fig. 8 is a section on the line 8—8, Fig. 3.

50 In the sewing machine shown in the drawings the stitch-forming mechanism comprises an upper needle 4 for manipulating the upper needle thread 5 and an under thread manipulating mechanism (not shown) carried by a turret situated beneath the bed 1, the needle 4 being carried by the usual needle bar 3 which reciprocates in the head 2. The 55 work-holding means is supported on the bed 1 and comprises the usual clamp plates 6 and work clamps 7 which are pivoted to the clamp plates at 8 and are constructed to clamp the work against the clamp plates. The buttonhole cutter is shown at 9 and is carried by a swinging arm 10 as usual in 60 sewing machines of this type. In the sewing machine herein shown the head 2 is mounted to move back and forth on the bed 1 thereby to provide for the relative movement between the stitch-forming mechanism and work-holding means above referred to and such movement is secured through the 65 operation of a main or feed cam (not shown) operating beneath the bed 1. Examples of buttonhole sewing machines of this type may be found in United States Patents No. 655,637, Aug. 7, 1900, No. 862,238, Aug. 6, 1907, to which reference may be had for a

more complete description of the means for operating the stitch-forming mechanism and for moving the head 2 relative to the work-holding means.

70 When the machine has been brought to rest at the end of a stitching operation the parts are in the relative position shown in Fig. 1, that is, the head 2 carrying the stitch-forming mechanism is in its forward position so that the buttonhole cutter 9, which is carried by the head 2, will be supported over the work clamp 7 and in position to cut the buttonhole in the work *w* when it is clamped by the work clamp 7. In this position the needle 4 will be situated in front of the buttonhole. When the machine is started and after the work clamps have clamped the work then the head 2 is given a movement to the right, Fig. 1 before the stitch-forming mechanism is set in operation thereby to carry the needle into the dotted line position Fig. 1, or in position to commence the stitching on the buttonhole, the buttonhole cutter by this movement being carried back out of the way. At this time the stitch-forming mechanism is set in operation, it being driven from the shaft 11 and the stitching is performed down one side of the buttonhole, around the eye of the buttonhole, and then back along the other side of the buttonhole and during this operation the head 2 will have a feeding movement first in one direction and then in the other. When the stitching on the buttonhole is completed the needle will be in the dotted line position Fig. 1 and before the machine comes to rest the head 2 is given a further movement to the left into the full line position Fig. 1. While this operation is common to buttonhole sewing machines of this type, yet I have thought it wise to rehearse it here as it would be a help in understanding the operation of my invention.

tends to maintain it in the positions shown in Figs. 2 and 8

The cutter 12 is situated directly beneath the plate 19 and the cutting edge 25 thereof operates to shear the thread directly beneath the plate 19 and the flange 23, as will be obvious from Fig. 8. The thread gripping device is arranged to grip the needle thread 5 at the end of each sewing operation so that when the machine comes to rest the end of the needle thread is held by the gripper as shown in Fig. 1.

As stated above the cutter 12 makes one cutting movement at the end of the stitching on a buttonhole and a second cutting movement at the beginning of the stitching at the next succeeding buttonhole and this is herein accomplished by forming the extension 17 of the arm 13 with the curved portion 26 that provides the two cam surfaces 27, 28 and by also providing the head 2 with a flange or arm 29 which engages these cam surfaces as the head moves back and forth during the cycle of operations.

Fig. 2 illustrates the position of the parts when the machine is brought to rest and the buttonhole has been cut and at this time the head 2 is in its forward position and the arm 29 engages the extension 17, as shown in Fig. 2, thereby holding the cutter in its forward position. At this time the needle occupies approximately the position indicated in Fig. 2 and the needle thread extends from the needle to the gripper shown in Fig.

1. When the sewing machine is started in operation the head 2 is first moved from buttonhole cutting position, shown in Fig. 1, into stitching position thereby to bring the needle into the dotted line position, Fig. 1, and into the position shown in Fig. 3. At this time the needle is in position to commence the stitching on the buttonhole and the end of the needle thread is still held by the gripper. The movement from stitching to buttonhole-cutting position is sufficient to carry the arm 29 into the curved portion 26 between the cam surfaces 27 and 28 as shown in Fig. 3. At this time the spring 16 acts to retract the cutter into the position shown in Fig. 3. The shaft 11 is now set in operation to start the stitch-forming mechanism and the head 2 has a slow feeding movement to the right, Fig. 1, to carry the stitching down one side of the buttonhole and during this movement the arm 29 engages the cam surface 28 thereby swinging the cutter forwardly into the dotted line position Fig. 3, this operation causing the cutter to cut the end of the thread which is held by the gripper. As the stitching around the buttonhole continues the head 2 will move to its limit to the right, Fig. 1 and then move to the left again in Fig. 1 until it arrives at the dotted line position, which is the position it assumes when the stitching on the

buttonhole is completed. At this time the arm 29 has again come into the position shown in Fig. 3 and when the head has its final movement from stitching to buttonhole cutting position or from the dotted line position Fig. 1 to the full line position the arm 29 will engage the cam surface 27, thereby causing the cutter to cut the thread between the needle and the work.

The thread gripping device is actuated by a pin or projection 30 carried by the head 2. The arm 21 of the gripper has an extension 31 on which is pivotally mounted a finger 32 that is provided at its lower end with a shoe 33 having the cam surfaces 34, 35. The finger 32 is acted upon by a spring 36 which normally holds it against a stop finger 37 carried by a collar 38 that is fast to the extension 31. This stop finger 37 limits the swinging movement of the finger 32 in one direction but said finger is free to swing in the opposite direction. Since the pin 30 is carried by the head 2 it moves back and forth with the head and said pin is so positioned that just before the stitching on a buttonhole has been completed, said pin will engage the cam surface 34 of the shoe and by acting thereagainst will swing the lever 21 from the position shown in Fig. 2 to that shown in Fig. 4. While the pin 30 is engaging the cam surface 34 the finger 32 is held against the stop 37 and therefore the action of the finger against the cam swings the arm 21 as above stated. This movement of the arm 21 carries the gripping member 20 across the line of stitching to the opposite side of the needle thread and the gripper 20 is maintained in this position until the head 2 has moved forward sufficiently to carry the pin 30 past the shoe 33. When the pin has moved past the shoe 33 then the spring 24 operates to return the gripper into its operative gripping position shown in Figs. 2 and 3. The parts are so timed that before the pin leaves the shoe 33 the portion of the needle thread extending from the work to the needle will lie between the hooked portion of the gripper 20 and the gripping member 19 so that when the pin 30 is carried past the shoe the movement of the gripping member from the position shown in Fig. 4 to that shown in Figs. 2 and 3 will cause the needle thread to be gripped between the flange 23 and the gripping member 19 as shown in Fig. 8. This occurs after the stitch-forming mechanism has come to rest and before the cutter 12 has its thread-cutting movement at the end of the stitching operation. Hence when the cutter operates to cut the thread at the end of the stitching operation the thread is held by the gripper and as the cutter operates between the gripper and the work end of the needle thread will be retained in the gripper.

When the machine is started in operation

again and the head moves from buttonhole-cutting position to stitching position the pin 30 again engages the shoe 33 but at this time it engages the cam surface 35 as shown in Fig. 5 and because the arm 32 is pivotally mounted on the extension 31 the shoe at this time is merely swung laterally away from the stop 37 and gives no movement to the thread-gripping member 20. The thread gripper 20 therefore is only operated at the end of the buttonhole when it is necessary to grip the needle thread. On the other hand the thread cutter is actuated twice, once at the beginning of the stitching operation and again at the end of the stitching operation.

I claim:

1. In a sewing machine constructed to sew a short seam and then come to rest, the combination with stitch-forming mechanism and work-holding means movable relatively to each other, said stitch-forming mechanism including a needle, of means operative at the end of each seam to grip the needle thread between the needle and the work, means to cut the thread between the gripper and the work, and means rendered operative by such relative movement to actuate first the thread gripping device at the end of each seam, then to actuate the cutter to cut the thread, and also to actuate the cutter a second time after the next succeeding seam has begun to be stitched.

2. In a sewing machine constructed to sew a succession of short seams and to come to rest at the end of each seam, the combination with stitch-forming mechanism and work-holding means movable relatively to each other, of means adapted to take and hold the needle thread between the needle and the work, a cutter having a cutting edge adapted to sever the thread between the holding means and work, and means rendered operative by such relative movement to cause the thread-holding means to take the needle thread after the completion of one seam and to hold it while the thread is severed and while a second seam is thereafter begun to be stitched, and also to cause the said cutting edge to cut the thread both at the end of each seam and after the starting of the stitching on the next seam.

3. In a sewing machine, the combination with work-holding means and stitch-forming mechanism having relative movement, of a thread holder, a movable thread cutter, means operated by said relative movement to cause the thread holder to grip the thread at the end of the seam and to give the thread cutter a thread-cutting movement both at the end of the seam and at the beginning of the seam.

4. In a buttonhole sewing machine, the combination with work-holding means, of stitch-forming mechanism movable relative

to the work-holding means while the edge 65 stitches are being formed on a buttonhole and having a further relative movement to carry the parts from stitching position to buttonhole-cutting position and vice versa, a thread-gripping device, a thread-trimming device, and means actuated by the relative movement of the stitch-forming mechanism to cause the thread-gripping device to grip the needle thread at the end of each buttonhole and to cause the thread-trimming device to trim the thread after it has been thus gripped and again after the stitching has commenced on the next buttonhole.

5. In a buttonhole sewing machine, the combination with work-holding means, of stitch-forming mechanism movable relative to the work-holding means while the edge stitches are being formed on a buttonhole and having a further relative movement to carry the parts from stitching position to buttonhole-cutting position and vice versa, a thread-gripping device, a thread-trimming device, means actuated by the movement of the stitch-forming mechanism from stitching position to buttonhole-cutting position at the end of each buttonhole to cause the thread-gripping device to grip the needle thread and the trimming device to trim said thread and by the feeding movement of the stitch-forming mechanism when the stitching on the next seam has begun to cause the trimming device to again trim the thread.

6. In a buttonhole sewing machine, the combination with work-holding means, of a frame carrying a stitch-forming mechanism and movable to produce a feeding movement during the formation of the stitches around a buttonhole and also movable to carry the parts from relative stitching position to relative buttonhole-cutting position, a thread-holding device, a thread-trimming device, means operative only during the movement of the frame which occurs at the end of each buttonhole to cause the thread-holding device to seize and hold the needle thread, and means rendered operative by the movement of the frame from stitching to buttonhole-cutting position to cause the trimmer to operate, and also rendered operative by the feeding movement when the stitching on a buttonhole begins to again cause the trimmer to operate.

7. In a sewing machine, the combination with stitch-forming mechanism and work-holding means movable relatively to each other, of a thread holder, a thread cutter having a cutting edge, means operative at the end of a sewing operation by the relative movement of the work-holding means and stitch-forming mechanism to cause the thread holder to grip the thread and thereafter to move the thread cutter to cause the cutting edge thereof to sever the thread,

said means also operating the thread cutter to cause said cutting edge to cut the thread at the beginning of the seam.

8. In a sewing machine, the combination with work-holding means and stitch-forming mechanism having a relative movement, of a thread holder, a movable thread cutter having a cutting edge, means operated by said relative movement to cause the thread

holder to grip the thread at the end of the seam and to move the thread cutter to cause said cutting edge to cut the thread both at the end of the seam and at the beginning of the seam.

In testimony whereof, I have signed my name to this specification.

JOHN KIEWICZ.
